UNITED STATES PATENT OFFICE.

PIERRE MALAVAL AND RENÉ PAQUELIER, OF PARIS, FRANCE.

PROCESS FOR THE RENOVATION OF WORN GUN BARRELS AND IMPROVEMENTS IN GUN BARRELS.

No Drawing. Application filed May 13, 1926, Serial No. 108,972, and in France August 3, 1925.

In our prior U. S. Patent No. 1,544,469 there was described and illustrated a removable lining tube arrangement for gun barrels, according to which a worn liner could 5 be removed and a new liner fitted into place without the gun barrel having to be returned to the workshop, this important result being due to the fact that as the liner was constructed of a metal having a very high elastic 10 limit and, in any case, an elastic limit considerably higher than that of the metal forming the outer tube, the initial clearance provided between the liner and the tube, after having been taken up at the moment of 15 the passage of the projectile, is restored immediately afterwards.

In the said prior patent formulae were given enabling the elastic limit to be possessed by the metal of the liner to be determined, so that it is considerably greater 20 than that of the metal of the same composition of which the outer tube is formed, a suitable clearance being allowed at the same time in order that the liners will not be 25 come permanently deformed when firing takes place, the immediate effect of which deformation would be to make them adhere to the metal of the tube and to make it as a consequence impossible to extract them without 30 employing complicated tools.

It has been discovered that in practice it is possible, to a certain extent, to reduce the difference between the elastic limit of the metal of the gun barrel and that of the liner 35 by compensating for this reduction in difference by a cold hardening. One of the most rational means for obtaining all together a small increase in the elastic limit of the metal of the liner and this compensating 40 cold hardening consists in subjecting a liner of ordinary gun steel to a self-hooping operation.

Self-hooping consists, as it is known, in producing a permanent deformation or set 45 by internal hydraulic or other pressure; this pressure has the effect of cold hardening the metal and raises by a notable extent the elastic limit. Further the special state produced by self-hooping, which is comparable 50 to the state of ordinary hooping, increases the elasticity of the liner and consequently assists in preserving the clearance between the liner and the gun barrel.

What we claim is:

55 1. A gun having an outer tube, an inner

tube of ordinary gun steel cold-hardened and self-hooping, the outer diameter of said inner tube being less than the inner diameter of said outer tube in the state of rest and adapted to expand to the inner diameter of 60 said outer tube under stress of firing.

2. A gun having an inner tube and an outer tube of ordinary gun steel, said inner tube being self-hooping to have a higher elastic limit than said outer tube, the normal 65 outer diameter of said inner tube in the state of rest being less than the inner diameter of said outer tube to leave a clearance therebetween, whereby said inner tube may be easily removed.

70 3. In a gun having inner and outer tubes and having clearance between the outer and inner diameters respectively thereof, an inner tube of the same material as said outer tube but strained beyond the elastic limit of 75 said material and thereby having a higher limit of elasticity than said outer tube.

4. In a gun having inner and outer tubes and having a clearance between the surfaces of said tubes in the state of rest whereby 80 said inner tube may be readily withdrawn from said outer tube, an inner tube of ordinary gun metal having the metal thereof strained beyond its limit of elasticity and thereby adapted to expand and be gripped by 85 said outer tube under stress of firing and to contract free of said outer tube after firing.

5. A gun comprising an outer tube of normal gun metal, an inner tube of gun metal normally having the same characteristics as 90 the metal of said outer tube but strained beyond its elastic limit, the outer diameter of said inner tube being less than the inner diameter of said outer tube in the state of rest, the deformation imparted to the metal of said inner tube permitting the latter to expand and be gripped by said outer tube under stress of firing and to contract free of said outer tube after firing.

95 6. A liner for a gun, said liner being self-hooped to increase the elastic limit thereof, the outer diameter of said liner being less than the inner diameter of the gun.

100 In testimony whereof we have signed this specification.

PIERRE MALAVAL.
RENÉ PAQUELIER.
